UNITED STATES PATENT OFFICE.

GEORGE BALLWEBER, OF CINCINNATI, OHIO.

ATTACHMENT FOR INTERNAL-COMBUSTION ENGINES.

Application filed October 16, 1919. Serial No. 331,038.

To all whom it may concern:

Be it known that I, GEORGE BALLWEBER, a citizen of the United States, and residing at Cincinnati, in the county of Hamilton and 5 State of Ohio, have invented a new and useful Improvement in Attachments for Internal-Combustion Engines, of which the following specification is a full disclosure.

This invention relates to carburetion, and 10 has for an object to provide an auxiliary water or moist vapor intake, connected at its one extremity to the intake manifold of an engine adjacent the carburetor, and at its opposite extremity, to the vapor-space 15 adjacent the top of the radiator, and to provide valve means for controlling the supply of said water-vapor to the intake manifold.

Another object is an arrangement for the 20 delivery of water-vapor to the interior of each engine cylinder, and the interposition of a manifold connection in the pipe-line between the top portion of the radiator and of the intake valve for each cylinder.

Other objects are to provide a simple 25 intake valve construction and a simple connection for the vapor supply pipe, at the upper portion of the radiator.

The advantages of mixing water-vapor 30 with the carbureted substances are well known, but I have provided a simple and improved apparatus for accomplishing the result, and admit of perfect control of the quantity of moist vapor delivered to the cylinders of an engine.

35 Additional objects and advantages are set forth in this specification and drawings, and specifically pointed out in the claims appended hereunto. Like numerals refer to corresponding parts throughout the drawings, of which:

Figure 1 is a side elevation of one form of 40 my invention, shown connected to a common type of engine, carburetor and radiator,

Figure 2 is a side elevation of a second 45 form of my invention, showing the same connected to the interior of the engine cylinders and to the radiator,

Figure 3 is a central vertical section of 50 my improved intake valve, and

Figure 4 is a central sectional view of 55 my improved connecting means for the vapor supply pipe at the radiator.

Figure 5 is a central vertical section of a 60 modified form of my intake valve.

The numeral 1 designates the radiator, 2

its filling opening and 3 its connection to engine 4. The intake manifold is indicated at 5, the carburetor at 6. The vapor line connection is made with the upper end of 60 the radiator by a short section of pipe 7, with an upturned portion 8 inserted into the radiator and rigidly secured at 9, to an exteriorly screw threaded plug 10. The plug 10 has a headed end 11 which bears against 65 the inside face of the rear wall 12 of the radiator.

The plug 10, with its pipe section 7, is inserted through an opening 13 in the rear wall 12 of the radiator, and the upturned 70 end 8 is positioned within the filler opening 2, to bring the inlet end at the highest point in the radiator above the filled water line of the radiator. A washer 14 is interposed between the head 11 and the radiator 75 casing, as shown, and a second washer 15 is placed upon the outside of the said casing and around the screw threaded plug, and a nut 16 is screwed thereagainst.

A second pipe 17 is secured to the tapered 80 end of the plug 10 by means of a threaded union 18, as shown. This pipe 17 is provided intermediate its length with a valve 19 having suitable control connection 20 extended to dash of the motor vehicle, actuated by means of button 21.

The connection of the pipe 17 to the pipe 85 section 7, and the novel manner of fastening the pipes to the radiator permits of the installation of a vapor pipe in a commercial 90 type of machine, without change therein, other than the provision of an opening in the vertical wall of the radiator. The horizontal disposition of the pipe 7 within the 95 radiator and its immersion in the heated water at the top of the radiator tends to maintain the temperature of the vapor delivered into the pipe through the outer upturned end of the same.

In the form shown in Figure 1, a short 100 pipe connection 22 is provided between the valve 19 and a check-valve 23, of unique construction. The valve 23 is composed of a hollow cylindrical base portion 24, provided with a conical lower outlet portion 25, the same being provided with an internally threaded nipple end 26, for the reception 105 of a short pipe section 27, connecting with the intake manifold, adjacent the carburetor 6, and is further provided with a threaded opening 28, in the hollow cylindrical portion, for the reception of the short 110

pipe section 22, connecting with the valve 19. This opening 28 communicates with an opening 29 formed in the side wall of a cylindrical valve plug 30, flanged at its top and provided with a central bore 31, communicating with the opening 28.

The cylindrical plug 30 is further provided at its top with an upstanding exteriorly threaded hollow cylindrical portion 32, for the reception of the upper end of the valve stem 34, and a spring 35 surmounting the same. The upper wall of the plug 30 is bored at 36 for the reception of the valve stem 34, the said stem being provided 15 with a valve head 37. The valve head proper is of substantially plano-convex configuration and has at its top an upstanding cylindrical boss 38 with outstanding centering lugs 39 formed thereon, and a central 20 depending pin 40 at its lower side. The boss 38 is integral with the valve stem 34. The valve head is seated at 41, against the lower portion of the plug 30, and is normally held against the same by the spring 25 35, the said spring bearing against a suitable stop 42 held in position by an adjusting nut 43. The upstanding cylindrical portion 32 is closed by a cap 44 and the plug 30 is held seated by fastening devices 45.

By adjusting the degree of tension of the spring 35, any desired amount of water-vapor may be admitted to the intake manifold at each suction stroke of the engine 35 cylinders.

Additional adjustments may be made by means of the valve 19 and its connections, and by the same means, the supply of water-vapor may be entirely cut off.

40 In the form of my device shown in Figure 2, a valve 23 is in communication with each engine cylinder, at its top, and each valve is connected, as at 49, to the manifold 50. From the central portion of the manifold, a short pipe connection 51 leads to the valve 19, and the said valve 19 is operatively connected to the rod 20, and button 21, to be controlled from the dash, precisely as in the first form of my invention.

45 The valve 19 has the pipe section 17, connected to the radiator, in precisely the same manner as described for the first form of my invention.

50 In this second form of my improvement, the water-vapor is drawn directly into each cylinder instead of into the intake manifold as in the first form of the same.

55 I have shown a modified form of intake valve 23 (see Fig. 5), composed of a hollow cylindrical body portion 60, provided at one side with an outstanding interiorly threaded boss 61, for the reception of the pipe section 22, and further provided with a centrally bored bottom 62, having in its

lower surface a conical valve seat 63, with a valve head 64 seated therein. The valve-stem 65, integral with said valve head 64, projects upwardly through an interior depending cylindrically bored guide-projection 66, integral with the body 60, and the valve-stem, at its upper threaded portion, is surrounded by a cylindrical spring-receiving chamber 67, formed integral with the body 60, and the outer wall of said chamber 75 is screw threaded for the reception of a closure-cap 68. A spring 69 surrounds the upper end of the valve-stem, seated against the bottom of the chamber 67, its upper coil is in contact, under compression, with an adjusting-nut 70, and a second lock-nut 71, and split-key 72, hold the said spring in proper adjusted position.

The bottom 62 provides a screw-threaded, depending projection 73, for the reception 85 of a cup-shaped cap 74, screwed to said projection 73, and said cap has a centrally bored and threaded nipple-end 75 for the reception of the pipe section 27.

Having described my invention, I claim: 90

1. In a device of the class described, the combination with an internal combustion engine, of a radiator connected therewith, adjustable automatically operated intake valves in central communication with the top of each engine cylinder, a pipe connection from each intake valve internally communicating with a distributing chamber, a pipe attached to and communicating with said chamber, and with the top interior of said radiator and a manually operated valve in said pipe for controlling vapor flow to said chamber. 95

100

2. In a device of the class described, in combination with an internal combustion engine, of a radiator connected therewith, adjustable automatically operated intake valves in central communication with the top of each engine cylinder, a pipe connection from each intake valve internally communicating with a distributing chamber, a pipe attached to and communicating with said chamber and with the top interior of said radiator, means for connecting said pipe to said radiator, said means comprising a headed and threaded hollow cylindrical plug projected through the top wall of said radiator, clamping and leak preventing means for said plug, a union screwed to said plug and fastened thereto with said vapor supply pipe, the portion of the pipe within the radiator being horizontally disposed and rigidly attached to said plug. 115

120

In witness whereof, I hereunto subscribe my name, as attested by the two subscribing witnesses.

GEORGE BALLWEBER.
